UNITED STATES PATENT OFFICE.

ROBERT J. SUNDBERG AND JOHN NELSON, OF AURORA, ILLINOIS.

HYDROCARBON-BURNER.

No. 885,105.

Specification of Letters Patent.

Patented April 21, 1908.

Application filed July 22, 1907. Serial No. 385,008.

To all whom it may concern:

Be it known that we, ROBERT J. SUNDBERG, a subject of the King of Sweden, and JOHN NELSON, citizen of the United States, 5 residing at Aurora, in the county of Kane and State of Illinois, have invented certain new and useful Improvements in Hydrocarbon - Burners, of which the following is a specification.

10 Our invention relates to improvements in hydrocarbon burners and its chief object is to provide a burner that will produce perfect combustion with the use of the comparatively heavy oils and especially of the grade 15 having a fire test of high degree and known commercially as kerosene.

Other objects of our improved burner are to provide a device for promoting the combustion of the fuel oil by leading the supply 20 to a generating chamber which is placed above the flame so that the heat therefrom will be used to the best advantage in vaporizing the oil; and to supply a burner of such 25 design that the fuel oil will be circulated in the proper quantity to afford a uniform combustion without requiring valves in the induction or eduction pipes.

We accomplish the above and other minor 30 results by the use of the device illustrated in the accompanying drawing which forms a part of this specification and in which:

Figure 1 is an elevational view of our improved burner attached to a portable stove, and Fig. 2 is a vertical section, enlarged, of 35 the burner detached.

Referring in detail to the drawing, the numeral 10 indicates a circular oil reservoir, 11 an air pump, and 12 the filling opening, the latter having a vent cock 13, for reducing 40 the pressure at will. The said reservoir is supplied with the usual supports 14 which are tubular in form to receive uprights 15, the upper ends of which are bent radially inwardly to form horizontal bars 16 upon 45 which utensils may rest while they are subjected to the action of the flame. The function of the air pump is the usual one to produce sufficient pressure above the oil to force it through the induction pipe 17 which is concentric with the reservoir 10 its lower open 50 end extending approximately to the bottom thereof, so that it will always be below the level of the fuel. The upper end of said pipe has a threaded connection with a tubular 55 stem 18, provided with an integral nut 19 to facilitate union, an ignition cup 20 being

held in position upon the upper end of the pipe 17 when assembled. The stem 18 has two hollow branches 21, 22, which project from opposite sides at different levels, the 60 lower branch 21 has a bore which communicates with the bore of the stem 18 and in turn is in communication with a tube 24 extending vertically upward and terminating in an annular ring 25 which forms the generating 65 chamber. An eduction tube 24^a placed diametrically opposite to the induction tube 24 forms a communication between the generating chamber and the said branch 22. The inner end of this branch terminates in a 70 nipple 23 which extends vertically upward and is threaded to receive a nozzle 23^a which is provided with a narrow orifice through which the generated gas is delivered in a 75 fine jet.

A short distance above the plane of the nozzle is located a diaphragm or shelf 26, horizontally disposed and having a central boss slightly elevated upon which rests a cylindrical shell or grid 27 formed of perforated 80 metal. Concentric with said shell is located a flue 28, open at both ends, the lower end being approximately at the level of said shelf 26 and the upper terminating at a point just below the upper margin of the hollow generating 85 ring 25. The area within said ring above the shell 27 and flue 28 is closed by a cap or cover 29, which fits loosely upon the ring so that it can be readily removed. The rim of the shelf 26 is upturned to form a 90 flange within which rests a conical upwardly flaring deflector 30. The flue 28 fits tightly in the shelf 26 and shell 27 at its lower end where it traverses those structures and is further secured by soldering and the shelf 95 and shell are in like manner supported upon the tubes 24, 24^a.

To operate the device the reservoir having been partly filled with oil so as to leave a space for the compression, a small quantity 100 of alcohol is poured into the ignition cup 20 and lighted. As soon as the burner has become sufficiently heated, the air pump 11 is operated to compress the air in the dome of the reservoir and this will force the oil 105 through the pipe 17 and connecting passages to the generating chamber 25. The capacity of this chamber is so proportioned to the fuel supply that the latter will become completely volatilized by the time it reaches the eduction 110 passage 24^a and the vapor will be projected in a fine stream vertically upward

from the nozzle 23^a through the flue 28 until it impinges against the under surface of the cap 29. There is a narrow interval between the upper margin of the flue 28 and said cap 5 and the vapor is deflected in every direction through this space, filling the cavity of the perforated shell 27 and finding exit through the orifices 27^a. As the jet issues from the nozzle 23^a and passes up into the flue 28 it 10 receives the proper admixture of air to produce complete combustion and this mixture when lighted at the orifices 27^a produces an annular flame made up of the multitude of minute flames issuing from the said orifices. 15 As the chamber 25 is located in the hottest zone of the ignited vapor it will supply a constant and uniform supply of vapor and the resulting flame will be devoid of smoke or odor. The vapor will continue to burn as 20 long as the oil supply is kept up from the reservoir.

It will be observed that there are no valves in the burner and none are required, and the vaporization is so complete and combustion 25 so perfect that the tendency to foul or clog has been reduced to almost *nil* the only possibility of stoppage of the ducts being at the nozzle, the fine bore of which may become clogged with dust or debris, but only when 30 the burner has lain unused for a considerable period of time. In case such a contingency should arise it is only necessary to remove the cap 29 and pass a fine wire through the bore of the nozzle, the lumen of which is

made slightly flaring to facilitate the entrance 35 of a cleaning wire.

It is evident that our burner may be used in heating apparatus of varied designs, and while we have shown our device as applied to a portable stove we do not wish to be limited 40 to its use to such apparatus.

Having thus described our invention what we claim is:—

1. A hydrocarbon burner, including a hollow stem, a partition in the bore of said stem, 45 two branches communicating with the bore of the stem upon opposite sides of said partition and extending vertically above the stem, said branches lying in the same vertical plane, an annular generating chamber 50 supported upon said branches and connected therewith, a perforated shell located beneath said generating chamber and concentric therewith, a vertical flue passing through an opening in the floor of said shell and supported thereby, the upper end of said flue extending approximately to the level of the upper margin of the said annular chamber, a removable cap supported upon said chamber, a removable nozzle in the upper end of said stem, 55 and a deflector surrounding the said shell.

In testimony whereof we affix our signatures in the presence of two witnesses.

ROBERT J. SUNDBERG.
JOHN NELSON.
